CLAIM

The ornamental design for a rack for supporting and dispensing coiled wire, as shown and described.

DESCRIPTION

FIG. 1 is a top, front, and left side perspective view of a rack for supporting and dispensing coiled wire showing our new design;

FIG. 2 is a front elevational view thereof;

FIG. 3 is a top plan view thereof;

FIG. 4 is a bottom plan view thereof;

FIG. 5 is a right side elevational view thereof;

FIG. 6 is a rear elevational view thereof, and,

FIG. 7 is a top, front, and left side perspective view thereof, the broken-line disclosure of coiled wire being for illustrative purposes only and forming no part of the claimed design.
